ROAD ROLLER

Alois Hamm, Tirschenreuth, Germany

Application April 10, 1937, Serial No. 136,167
In Germany September 23, 1935

12 Claims. (Cl. 94—50)

The present invention relates to a road-roller, more particularly to a three-roll roller or a roller of the so-called tandem type in which the position of the front and rear rollers can be changed with respect to one another.

5 It is an object of the present invention to provide a road-roller of the type referred to, the rolling width of which can be changed as long as the roller is standing still as well as when it is in motion.

10 An object of the present invention resides in the provision of a road-roller of such design that the formation of undesired undulations on the road surface is avoided.

15 Another object of the present invention is to provide a road-roller in which the fork-shaped bow members or axle-holders for holding the front and rear rollers are situated horizontally and in which said members are provided with 20 transverse parts which are individually provided with curved surfaces which abut one another and are located between and guided by plate-shaped parts, which parts carry bolts which are adapted to cooperate with and move in curved slots provided in said transverse members, and 25 one of said parts being adapted to carry the driving motor of said road-roller, the driving mechanism and other equipment of the road rolling machine.

30 It is a further object of the present invention to provide a road-roller, the effective rolling width of which can be adjusted at any operating condition of the roller and in which the position of the axes of the rollers can be changed individually with respect to one another when the machine is standing still as well as when it is in motion, whereby movement of the machine through curves and at voluntarily variable effective rolling width is made possible. With the 35 mechanism according to the present invention, the position of the axis of each individual roller can be changed while that of the other roller is not changed, and it is also possible to change the position of front and rear rollers simultaneously.

40 45 With conventional road-rollers, undulations on the road surface are caused by the substantially horizontally swinging motions made by the upright bows. Due to the horizontally positioned and abutting bows of the machine according to 50 the present invention, this disadvantage is eliminated.

The present invention is applicable to three-roller machines as well as to tandem machines and can be used in combination with steam power 55 or other power drives.

Further and other objects of the present invention will be hereinafter set forth in the accompanying specification and claims and shown in the drawings which, by way of illustration, show what I now consider to be a preferred embodiment of my invention.

In the drawings:

Fig. 1 is a side view of a road-roller according to the present invention with parts broken away.

Fig. 2 is a top view of a road-roller according to the present invention, the motor and driving mechanism of which are omitted in order to make the showing of the invention clearer.

Fig. 3 is a top view of a road-roller according to the present invention, the individual rollers of 15 which are in position for increased effective rolling width.

Fig. 4 is a top view of a road-roller according to the present invention, the individual rollers of 20 which are in position for moving around curves.

Referring more particularly to the drawings: the axles 2 and 2' of the rollers or rolling drums 1 and 1' carry the horizontally positioned axle-holders or bow members 3 and 5. Member 3 is provided with a curved surface 3' forming part 25 of a cylinder with substantially vertical axis. A curved surface 4' is provided also in connection with member 5. The bow members 3 and 5 are adapted to move in between guiding members such as the plate-shaped members 14 and 15 of 30 the illustrated embodiment. The guiding members 14 and 15 are interconnected by means of bolts 6 and 6' and pressed together by springs 23 and 23', respectively, which are associated with said bolts and permit movement of said bolts in 35 the direction of their longitudinal axes. The upper member 15 carries the motor 19, the gear box 1, and other equipment of the machine which are not shown in detail because they do not form part of the present invention. At least one of 40 the axle-holders, in the embodiment of the present invention shown, axle-holder 5, may be provided with an intermediary part 4 which is connected with axle-holder 5 in such manner that vertical motions of one part relative to the other 45 are possible. Part 4 is provided with said curved surface 4' which abuttingly cooperates with the previously mentioned surface 3'. Bolts 6 and 6' are adapted to move in the curved slots 17 and 17' of members 3 and 4, respectively.

50 The transverse parts of the members 3 and 4 are hollow and provided with toothed rims 13 and 13' with which pinions 16 and 16' cooperate, which pinions are revolvably secured to said members 14 and 15. If one of the pinions 16 55

and 16' is turned, the position of the axis of the roller with which it is associated is changed. Turning of pinion 16 and/or 16' is effected by revolving the hand wheels 18 and/or 18'. To these hand wheels, bevel gears 20 and 20', respectively, are connected which are individually connected to and adapted to drive shafts 21 and 21', respectively, to which spur gears 22 and 22' are connected, respectively. These spur gears 10 are connected to and adapted to individually drive pinions 16 and 16', respectively. By manipulation of the hand wheels 18 and/or 18', the position of the axes of rollers 1 and/or 1' is changed jointly or individually.

15 Connected with one of the guide members 14 and 15 are wedge-shaped parts 12 which, at the position of the mechanism shown in Fig. 2, fill the space between the curved surfaces 3' and 4' and the members 14 and 15 and thereby aid in the 20 stability of the machine.

By suitable operation of the pinions 16 and 16', the position of the axes of rollers 1 and 1' may be changed in such a manner that said axes move parallel to one another, whereby the operating 25 width of the machine is changed as is shown in Fig. 3, or the angle enclosed by the axes 2 and 2' is changed as shown in Fig. 4, whereby the machine is adapted to move around curves of any radius. By suitable combination of an operation 30 according to Fig. 3 and Fig. 4, any rolling width can be adjusted also when moving around curves. On turning pinion 16 and/or pinion 16', bolt 6 and/or 6' moves in the guide slot 17 and/or 17'. Due to the friction of surfaces 3' and 4' of the 35 gears 20, 20', 22, and 22', the once adjusted position of the axes 2 and 2' remains until the next adjustment takes place.

The power of motor 19 is transmitted through suitable gearing, which is located in box 7 and not 40 shown in detail because it is not a part of the present invention, to shafts 8 and 8' which are provided with universal joints 24, 25 and 24', 25', respectively, and which shafts by means of bevelled gears 9 and 9', respectively, drive spur gears 45 10, 11 and 10', 11', respectively. Gear wheels 11 and 11' are connected with and drive rollers 1 and 1', respectively.

While I believe the above described embodiments of my invention to be preferred embodiments, I wish it to be understood that I do not desire to be limited to the exact details of design 50 and construction shown and described, for obvious modifications will occur to a person skilled in the art.

55 What I claim is:

1. In a road roller, the combination of at least two rolling drums, an axle and a substantially horizontal axle-holder for each of said drums, said axle-holders being arranged substantially at 60 one side of their associated drums so as to face each other, a guiding member on top of said axle-holders and between said drums for holding said axle-holders in a substantially horizontal plane, said axle-holders being movably connected to said 65 guiding member so as to be rotatable relatively thereto, and an individually controllable gear for each of said drums on said guiding member for altering the positions of said axle-holders, independently of each other, relatively to said guiding member.

70 2. In a road roller, the combination of at least two rolling drums, an axle and a substantially horizontal axle-holder for each of said drums, said axle-holders being arranged substantially at one 75 side of their associated drums respectively and

having bow-shaped portions so arranged as to abut against each other with said bow-shaped portions, and a guiding member on top of said axle-holders and between said drums for holding said axle-holders in a substantially horizontal plane, said axle-holders being movably connected to said guiding member so as to be individually rotatable relatively thereto.

3. In a road roller, the combination of at least two rolling drums, an axle and a substantially horizontal axle-holder for each of said drums, said axle-holders being arranged substantially at one side of their associated drums respectively and having bow-shaped portions so arranged as to abut against each other, with said bow-shaped 15 portions, a guiding member on top of said axle-holders and between said drums for holding said axle-holders in a substantially horizontal plane, and means on said guiding member for individually turning said holders relatively to said guid- 20 ing member.

4. In a road roller, the combination of at least two rolling drums, an axle and a substantially horizontal axle-holder for each of said drums, said axle-holders being arranged substantially at one side of their associated drums respectively and having bow-shaped portions so arranged as to abut against each other with said bow-shaped 25 portions, and two guiding members between said drums, one of said guiding members being ar- 30 ranged above the other one for holding said axle-holders in a substantially horizontal plane, said axle-holders being arranged between said guiding members and movably connected thereto so as to be individually rotatable relatively thereto. 35

5. In a road roller, the combination of at least two rolling drums, an axle and a substantially horizontal axle-holder for each of said drums, said axle-holders being arranged substantially at one side of their associated drums respectively 40 and having bow-shaped portions so arranged as to abut against each other with said bow-shaped portions, two guiding members between said drums, one of said guiding members being ar- 45 ranged above the other one, for holding said axle-holders in a substantially horizontal plane, said axle-holders being arranged between said guiding members, and means on the upper guiding member for individually turning said holders relatively to said guiding members. 50

6. In a road roller, the combination of at least two rolling drums, an axle and a substantially horizontal axle-holder for each of said drums, said axle-holders being arranged substantially at one side of their associated drums respectively 55 and having bow-shaped portions so arranged as to abut against each other with said bow-shaped portions, two guiding members, one above the other one, for holding said axle-holders in a sub- 60 stantially horizontal plane, said guiding member being resiliently connected to each other, said axle-holders being arranged between said axle-holders and movably connected thereto, so as to be individually rotatable relatively thereto. 65

7. In a road roller, the combination of at least two rolling drums, a substantially horizontal axle and an axle-holder for each of said drums, said axle-holders being arranged substantially at one side of their associated drums respectively and having bow-shaped portions so arranged as to 70 abut against each other with said bow-shaped portions, two guiding members, one above the other one, for holding said axle-holders therebetween in a substantially horizontal plane, and connecting bolts for said guiding members, said 75

bolts engaging said holders respectively in curved slots provided in said holders so as to permit said axle-holders to rotate relatively to said guiding members.

5 8. A device as claimed in claim 7 in which each bolt is provided with a spring bearing against one of said guiding members to hold them in resilient engagement with said axle-holders.

9. A road roller comprising at least two drums, 10 an axle and a substantially horizontal axle-holder for each of said drums, a motor and a transmission for driving said drums, said axle-holders being arranged substantially at one side of their associated drums respectively and having bow-shaped portions so arranged as to abut against each other with said bow-shaped portions, two guiding members between said drums, one of said guiding members being arranged above the other one, for holding said axle-holders therebetween in a substantially horizontal plane, and controllable means for individually turning said axle-holders relatively to said guiding members, said motor and transmission and said controllable means being mounted on said upper guiding member.

25 10. In a road roller, the combination of at least two rolling drums, an axle and an axle-holder for each of said drums, said axle-holders having bow-shaped portions and being so arranged as to abut against each other with said bow-shaped portions, two guiding members, one above the other one, for holding said axle-holders therebetween in a substantially horizontal plane, connecting bolts for said guiding members, said bolts engaging said axle-holders respectively in curved slots provided therein, toothed surfaces in rigid connection with said axle-holders respectively, pinions in

engagement with said toothed surfaces of said axle-holders and pivoted in said guiding members, and individual driving means for said pinions on top of said upper guiding member.

11. In a road roller, the combination of at least two rolling drums, an axle and an axle-holder for each of said drums, said axle-holders having bow-shaped portions and being so arranged as to abut against each other with said bow-shaped portions, a guiding member for holding said axle-holders in a substantially horizontal plane, wedge-shaped members between said axle-holders and attached to said guiding member, bolts for movably connecting said axle-holders respectively to said guiding member, said bolts engaging said 15 axle-holders in curved slots provided therein, and means for individually turning said axle-holders relatively to said guiding member.

12. In a road roller, the combination of at least two rolling drums, an axle and a substantially 20 horizontal axle-holder for each of said drums, said axle-holders being arranged substantially at one side of their associated drums respectively and having bow-shaped portions so arranged as to abut against each other with said bow-shaped portions, at least one of said axle-holders consisting of parts with a limited freedom of motion in vertical direction relative to each other, to permit vertical movement of the corresponding axle 25 relatively to the corresponding bow-shaped portion, and a guiding member for holding said axle-holders in a substantially horizontal plane, said axle-holders being movably connected to said guiding member so as to be individually rotatable relatively thereto.

35 ALOIS HAMM.
